UNITED STATES PATENT OFFICE.

CHESTER T. MCGILL, OF ELGIN, ILLINOIS, ASSIGNOR TO ELGIN SOFTENER CORPORATION, OF ELGIN, ILLINOIS, A CORPORATION OF ILLINOIS.

DECONCENTRATOR.

Application filed May 5, 1927. Serial No. 189,110.

This invention relates to improvements in internal blow-down systems or deconcentrators.

An object of this invention is to provide means for accumulating the scale forming solids and at the same time enabling the operator to remove the solids with little expense due to the loss of heat units, hot water, or otherwise.

10 The equipment, according to this invention, provides an efficient combination with a boiler for the self-cleaning thereof, whereby the frequent blow-down of the boiler is eliminated.

15 A further object of this invention is to provide a deconcentrator or internal blow-down system which will entirely eliminate the accumulation of suspended solids in a boiler, and by means of which a boiler may 20 be kept clean while in operation without excessive blowing-down and without washing the boiler out by hand at regular intervals.

One of the principal objects of this invention is to provide a system which will accomplish 25 advantageous results in connection with small boilers, particularly steam shovels and locomotive boilers where the expense or the placing of a settling chamber on the exterior of the boiler is impractical 30 owing to the lack of space or for other reasons.

This invention is an improvement over the inventor's Patent No. 1,593,700. The main difference in this particular invention consists in the creating of a circulation of boiler 35 water and scale forming solids while in a suspended form, through a quiet chamber or precipitating tank within the boiler where the solids are precipitated from the water in circulation, and the water is carried from 40 the precipitating tank into the circulation of the boiler water.

Other objects of this invention will appear from the following detailed description 45 of the device disclosed in the two sheets of drawings which are herewith made a part of this application.

In the drawings—

Figure 1 illustrates a side sectional elevational view of a return tubular boiler.

Figure 2 represents an end sectional view of the boiler, taken along line 2—2 of Figure 1.

Figure 3 illustrates a side elevational view

of the precipitating chamber, with parts 55 broken away.

Figure 4 represents an end view of the precipitating chamber.

Figure 5 illustrates a supporting method for attaching the precipitating chamber to 60 the interior of the boiler.

Figure 6 illustrates a sectional view of a fitting provided with a funnel arrangement through which steam bubbles pass and create a circulation of water from the sedimentation chamber 3.

When a boiler is in operation, making steam, the heat evaporating the water into steam, the steam bubbles naturally seek their place above the water level in the boiler 1, 70 and this is what creates a circulation of the water. As a portion of the steam bubbles will find their way within a funnel portion 2, these steam bubbles will seek the water line, carrying with them a circulation of water 75 into a settling or precipitating chamber 3. The water is carried from the entering end of the settling chamber as at 2, and flows through to the opposite end of the settling chamber 3, and out through a suitable fitting 80 4 on the opposite end of the precipitating or settling chamber 3. The fitting 4 is provided with a funnel arrangement 5 through which steam bubbles pass and create a circulation of water from the settling chamber 85 3. The two funnels 2 and 5, at each end of the chamber 3, create and maintain the circulation of water therethrough. The steam bubbles entering the funnel 2 naturally seek an outlet above the water line and are carried 90 into the steam space within the boiler through openings 6 along the top of the settling chamber 3.

In this invention, the suspended solids will accumulate in the bottom portion of the 95 settling chamber 3 and concentrate there in a very heavy, thick form from which they may be readily blown down by the opening of the valve 7 through the blow-down 8 and 9 which are connected in open communication with a perforated blow-down pipe 10 positioned within the chamber 3 and having a series of openings 11 for the purpose of 100 equally discharging the water from chamber 3 to the blow-down pipe line 10. The precipitation of the suspended matter will accumulate so heavily and thick within the 105 settling chamber 3 that in blowing out ten

or fifteen gallons of water from the chamber 3, the water will carry all the way from one-third to one-half solid matter or precipitated scale in the form of mud or sludge.

5 Figure 5 merely illustrates a form or method for securely strapping the precipitator 3 to the boiler tubes. This can be accomplished by means of a suitable number of clamping or strapping elements 12 or by 10 any other means which will hold the precipitator 3 in operable relationship within the boiler 1.

The fitting 4 on the opposite end of the precipitating or settling chamber 3 may be 15 of any suitable type of structure having an injector or siphon arrangement, such as disclosed in Figure 6 of the drawings, for the purpose of inducing the flow of water from the sedimentation chamber 3. The type of 20 device disclosed in Figure 6 clearly illustrates a preferred form, open at the top and bottom, thereby providing a means for the steam bubbles and water in the natural current and circulation of the boiler water to 25 pass into the funnel 5 up through the nozzle and siphon water from the sedimentation chamber 3. The water that passes up through the nozzle, together with the water 30 drawn from the sedimentation chamber, flows through the top of the fitting 4, the water then passing down into the natural current of the boiler water and passes away in circulation. The fitting 4 aids materially 35 in regulating the rapidity of the flow of water that passes through chamber 4, thus regulating the flow so that a sufficient amount of water will pass through the sedimentation chamber at a rate which will allow sedimentation to take place. The fitting 2 also 40 functions to pick up steam bubbles and hot water from the natural circulation of the water in the boiler and passes it into the sedimentation chamber 3, where the steam bubbles leave the water and the water travels 45 to the outlet. During the course of water traveling in the sedimentation chamber 3, the precipitation of the suspended solids takes place and the purified water is carried back into the boiler proper. The principle 50 of operation of the sedimentation chamber is that the water in the boiler outside of the chamber is in continuous agitation during the operation of the boiler, but, while passing through this sedimentation chamber, it 55 is comparatively quiet, thereby allowing the suspended solids to settle from the water before the water reenters the boiler proper. The sedimentation chamber may be of any shape or form which would function to make 60 it adaptable for different styles of boilers, and it may have as many supply inlets, similar to the inlet 2 and discharge outlet or ejector nozzles, as at 4, as may be required. 65 Also the steam outlet from the chamber 3 may have as many or as few openings as re-

quired similar to the openings designated by the numeral 6.

Number 13 represents a location for a safety valve, 14 a manhole and 15 a steam outlet for the boiler, while number 16 shows 70 the water level in the boiler, and 17 the water level in the sedimentation chamber.

This invention provides a deconcentrator or internal blow-down system which will enable the operator to keep the boilers clean 75 while in operation without excessive blowing down, particularly a type of small boilers, steam shovels and the like, wherein it is not practical to have a settling chamber on the exterior of the boiler as disclosed in 80 this inventor's Patent No. 1,593,700. The boiler may be operated in the usual way, the scale forming solids being chemically treated in order to prevent the formation of scale, the prime purpose of this invention being to 85 create a movement of the boiler water with its suspended scale forming solids through a quiet chamber or precipitating tank within the boiler where the solids are precipitated from the water passing therethrough and 90 the water is then carried from the precipitating tank into the circulation of the boiler water.

In this invention, the scale forming solids will accumulate in such a manner as to 95 allow the operator to remove them at a minimum expense, in time, loss of heat units, hot water and the like. As a matter of fact, this system provides means for self-cleaning the boiler and eliminates the need for frequent 100 blowing down, as under ordinary circumstances, where it becomes necessary to remove the boilers from the line, empty them and clean them out in order to get rid of the 105 concentration of scale forming solids which accumulate by the continued evaporation of water. A boiler, by this invention, can be kept clean while in operation.

The water and steam bubbles entering element or elements 2, pass into the setting chamber 3, where the steam bubbles are separated from the water and pass into the steam space of the boiler through openings 6. The precipitated solids carried with the steam bubbles and water into settling chamber 3 through element 2, settle into the quiet space at the bottom of chamber 3.

The functioning of the element 4 is on the same principle as in element 2, except that the steam bubbles do not pass into chamber 3. The steam bubbles pass up through special fitting 4 and means 4^a therein for creating a circulating effect on water through chamber 3. This water together with the steam bubbles and water in the circulation 125 of the boiler water, passes up through the top of element 4 and helps to regulate the amount of water which passes through chamber 3.

It is understood that there may be any 130

number of the supply elements 2 or discharge elements 4 connected to chamber 3 located other than at the ends of the chamber.

5 It is also understood that this method of accumulating precipitated solids in a chamber within a boiler is different from methods formerly employed wherein the circulation of boiler water was created by feeding 10 the boiler feed water into the chamber illustrated as 3.

With this arrangement, the boiler feed water does not enter and the advantage is that it operates whether water is being 15 pumped to the boiler or whether the boiler feed pump is lying idle; so long as there is any fire or heat under the boiler and any steam being made, this arrangement continues to operate and there is no possibility 20 of the chamber becoming inefficient through the concentration of scale forming solids.

What I claim is:—

1. In combination with a boiler, a sedimentation chamber located within the boiler 25 having a capacity sufficient to permit the separation of suspended solids from the water passing therethrough, means for diverting into the chamber a mixture of steam and water from a normal current of water 30 circulating in the boiler, means spaced relatively far from the diverting means for returning purified water from the chamber to the boiler, means for discharging steam from the chamber into the boiler, means for 35 discharging precipitated solids from the chamber to the outside of the boiler, means for coacting with the returning means to induce flow through the sedimentation chamber.

40 2. In combination with a boiler, a sedimentation chamber located within the boiler having a capacity sufficient to permit the separation of suspended solids from the water passing there through, means for diverting into the chamber a mixture of steam and water from a normal current of water 45 circulating in the boiler, means spaced relatively far from the diverting means for returning purified water from the chamber to the boiler, means for discharging steam from the chamber into the boiler, means for discharging precipitated solids from the chamber to the outside of the boiler, in which said discharging means for precipitated solids 50 comprises a blow down pipe line having an end thereof within the chamber adjacent the bottom thereof, and perforated extensions in open communication with said end, said perforations being downwardly directed, and 55 means for coacting with the returning means to induce flow through the sedimentation chamber.

60 3. In combination with a boiler, a sedimentation chamber located within the boiler 65 having a capacity sufficient to permit the

separation of suspended solids from the water passing there through, a funnel-shaped device for diverting into the chamber a mixture of steam and water from a normal current of water circulating in the boiler, 70 means spaced relatively far from the diverting means for returning purified water from the chamber to the boiler, means for discharging steam from the chamber into the boiler, means for discharging precipitated 75 solids from the chamber to the outside of the boiler, and means for coacting with the returning means to induce flow through the sedimentation chamber.

4. In combination with a boiler, a sedimentation chamber located within the boiler having a capacity sufficient to permit the separation of suspended solids from the water passing there through, a funnel-shaped device for diverting into the chamber 80 a mixture of steam and water from a normal current of water circulating in the boiler, means spaced relatively far from the diverting means for returning purified water from the chamber to the boiler, means for discharging steam from the chamber into the boiler, means for discharging precipitated 85 solids from the chamber to the outside of the boiler, means for coacting with the returning means to induce flow through the sedimentation chamber, and a suitably formed fitting connected with the returning means 90 for creating a uniform circulation of water through the chamber.

5. In combination with a boiler, a sedimentation chamber located within the boiler having a capacity sufficient to permit the separation of suspended solids from the water passing there through, a funnel-shaped device for diverting into the chamber 100 a mixture of steam and water from a normal current of water circulating in the boiler, means spaced relatively far from the diverting means for returning purified water from the chamber to the boiler, means for discharging steam from the chamber into the boiler, means for discharging precipitated 105 solids from the chamber to the outside of the boiler, means for coacting with the returning means to induce flow through the sedimentation chamber, said returning means comprising a fitting having an inlet connected with said chamber, an outlet to the boiler, a second inlet communicating with the boiler below the water level, means in said second 110 inlet for creating a uniform circulation of water through the chamber, and a funnel-shaped device attached to said second inlet. 115

6. In combination with a boiler, a sedimentation chamber located within the boiler having a capacity sufficient to permit the separation of suspended solids from the water passing there through, a funnel-shaped device for diverting into the chamber 120 a mixture of steam and water from a 125

normal current of water circulating in the boiler, means spaced relatively far from the diverting means for returning purified water from the chamber to the boiler, means for discharging steam from the chamber into the boiler, means for discharging precipitated solids from the chamber to the outside of the boiler, means for coating with the returning means to induce flow through the sedimentation chamber, said returning means comprising a fitting having an inlet

connected with said chamber, an outlet to the boiler, a second inlet communicating with the boiler below the water level, means in said second inlet for creating a uniform circulation of water through the chamber, a funnel-shaped device attached to said second inlet, and suitable means for holding the chamber in operative relationship within the boiler.

In testimony whereof I affix my signature.

CHESTER T. MCGILL.
